UNITED STATES PATENT OFFICE.

CHARLES T. TAR PENNING AND OTTO SCHELLERT, OF INDIANAPOLIS, INDIANA.

ACETYLENE-GAS GENERATOR.

1,178,426.

Specification of Letters Patent.

Patented Apr. 4, 1916.

Application filed April 9, 1914. Serial No. 830,719.

To all whom it may concern:

Be it known that we, CHARLES T. TAR PENNING and Otto SCHELLERT, citizens of the United States, residing at Indianapolis, in the county of Marion and State of Indiana, have invented certain new and useful Improvements in Acetylene-Gas Generators, of which the following is a specification.

10 This invention relates to acetylene gas generators which are particularly applicable to be used for generating acetylene gas for lighting purposes where artificial coal gas is not available.

15 The object of the invention consists in the provision of a gas generator of the above character which includes a secondary carbide-receptacle for holding carbide independently of the carbide in the main receptacle, which carbide will be automatically fed into the generating chamber at predetermined periods of time when the carbide in the main receptacle is exhausted, so that the lights may be continued for a greater length of 25 time, and also indicating both that the reserved carbide is being drawn upon and that the re-filling of the main carbide receptacle is imperative.

A further object of the invention consists 30 in the provision of a gas generator of the above character wherein a high grade of gas can be economically produced, the generator being automatically operated by the variation in the volume of gas within the 35 bell, until the carbide is entirely exhausted.

A further object of the invention consists in the provision of a gas generator of the above character embodying construction to reduce the liability of leakage of gas 40 to a minimum, thereby preventing waste of gas and possible loss of both life and property through explosion.

We accomplish the above objects of the invention by means of the construction 45 illustrated in the accompanying drawings, forming a part hereof, in which—

Figure 1 is a view partly in side elevation and partly in section of our improved acetylene gas generator. Fig. 2 is a sectional view on the line 2—2 in Fig. 1. Fig. 3 is a top or plan view of the generator. Fig. 4 is a top or plan view of the carbide-receptacle, the other portions of the generator being omitted. Fig. 5 is a cross section 50 on the line 5—5 in Fig. 4. Fig. 6 is a horizontal section on the line 6—6 in Fig. 5.

Fig. 7 is a vertical section on the line 7—7 in Fig. 5.

Referring to the drawings, 10 represents the main generating chamber which is preferably formed as shown in Fig. 3 of the drawings. The chamber is divided by means of a horizontally disposed diaphragm 11 having a vertically disposed throat-piece 12 through which the carbide passes from the carbide-receptacle to the water within the generating chamber 10. 15 represents the carbide-receptacle which is easily inserted into the upper end of the throat-piece 12, the introduction of said receptacle 15 being limited by means of a plurality of straps 16. The floor 17 of the carbide-receptacle 15 has a cone-shaped formation, in the usual manner, so as to feed the carbide to the center by gravity and through the discharge opening 18. The flow of the carbide through the opening 18 is regulated by means of a valve 19 which is attached to the lower end of the valve-rod 20 which extends vertically through the center of the carbide-receptacle 15. The upper end of the valve-rod 20 is engaged by means of a lever 21 which is pivoted in a standard 22, the free end of the lever sustaining a weight 23 which holds the valve 25 to normally close the opening 18. The valve-rod 20 is depressed when the gas is nearly exhausted from the bell so that a new charge of carbide is discharged into the generating chamber to renew the supply of 30 gas in the bell. In order to prevent leakage of gas around the carbide-receptacle 15 the latter is entirely inclosed by means of a hood 25 the lower end of which is sealed by the water 26 above the diaphragm 11.

35 30 represents the gas holder or bell wherein the excess of gas is stored, the said bell being confined within the hollow shell 31, the bell being free to move vertically as the volume of gas is increased, as shown by means of the dotted position in Fig. 1. As the gas is withdrawn from the bell 30 the latter descends, and when it has almost reached the limit of its downward travel it actuates the lever 33 through the chain 34, the lever 33, by means of the chain connection, being unaffected by the upward travel of the bell 30. The lever 33 extends across the top of the hood 25 and is pivoted to the standard 36 at 37. Through this connection the hood 35 is depressed when the lever 33 is acted upon by the bell 30 until said hood contacts

with valve-rod 20 when the valve 19 is opened and a new charge of carbid is discharged into the generating chamber. As a new supply of gas is generated the gas 5 passes out of the generator into the throat-piece 12 and thence into the outlet pipe 40, at which time sufficient pressure exists within the hood 25 to raise the latter sufficiently to clear the end of the valve-rod 20. As 10 soon as the weight of the hood has been removed from the valve-rod 20 the valve 19 closes the opening 18 by means of the counterweight 23.

It will be noted that the valve-rod 20 is 15 provided with a second valve 42 which is situated upon said rod a short distance above the valve 19. The object of the valve 42 is to prevent, in case the valve rod 20 is pushed entirely down and remains so for 20 any cause, the entire contents of the carbid receptacle being discharged through the discharge opening 18.

As before stated, the gas passes from the generating chamber through the pipe 40 25 into a chamber situated in the lower end of the shell 31, said chamber being divided by means of a horizontal floor 46 in the shell 31. The chamber in the lower portion of the shell is divided into two compartments 30 47 and 48 by means of the vertical division wall 49. As the gas is discharged from the pipe 40 into the compartment 47 it contacts a baffle-plate 50 whereby the gas is forced downwardly around the lower edge of said 35 plate and through the water 51 where the impurities are removed from the gas. The gas in the compartment 47 passes upwardly through the pipe 55 arranged vertically within the bell 30 and discharges therein 40 through a washer 56. The excess moisture in the gas is allowed to drain back down through the pipe 55 into the compartment 47. When the gas is being consumed the bell, which is being held in suspension by 45 the buoyancy of the gas, descends forcing the gas to pass out through the pipe 60 to the service pipe 65. We provide a loose connection between the ends of the pipes 60 and 65, the upper end of the pipe 60 being 50 enlarged as at 67 which is filled with suitable fluffy material to extract whatever moisture may be retained in the gas after passing through the washer 56. The adjacent end of the pipe 65 is provided with 55 an enlarged sleeve 70 which fits down loosely over the enlargement 67 on the pipe 60, the lower end of the sleeve 70 being sealed by the water above the diaphragm 11.

Examining Fig. 3, it will be noted that 60 access may be had to the generating chamber through an opening 75 through which the sludge may be removed and the cleaning of said chamber effected. The opening 75 is normally closed by means of a lid 76, 65 and said lid is provided with a handle 77

which extends a considerable distance above the generating chamber. This enables the lid 76 to be easily removed from the top of the ground when the generator is let into a pit in the ground, which is the desirable way 70 of construction, as it saves space, removes it from view and renders it less liable to be tampered with by unauthorized persons.

It has heretofore been mentioned that the generator is provided with certain means 75 whereby a portion of the carbid is confined separately from the major portion, so that instead of allowing the lights to be extinguished without warning when the major portion of the carbid is exhausted, the small 80 reserve supply can be drawn upon. As the reserve carbid is only released after the gas is almost entirely withdrawn from the bell, and with the resulting reduction in pressure of the gas at this time will show a corresponding reduction in the brilliancy of the 85 lights, and as the increased illumination of the lights immediately takes place after additional gas is generated from the reserve carbid, it acts as a signal to indicate that 90 the reserve carbid is now being drawn upon so that further consumption of gas can be controlled for the time being, and further indicating that the time for re-filling the main carbid-receptacle is near at hand. This 95 is accomplished by means of a semi-circular gate 80 which divides the carbid-receptacle into two compartments. The gate 80 is pivoted at each end to the walls of the carbid receptacle 15 and is actuated, to allow 100 the confined carbid to escape toward the discharge opening 18, by means of the operating-rod 81 which extends vertically through the carbid-receptacle and pivotally engages the lever 82 which is pivotally supported in 105 the standard 83. The free end of the lever 82 extends beneath the lever 21 and is actuated thereby when the lever 21 is sufficiently depressed to engage the lever 82. Ordinarily when the lever 21 is depressed 110 by the valve-rod 20 to unseat the valve 19 the lever 82 is not affected, this occurring only when the gas is almost entirely withdrawn from the bell 30 and the latter descends to such an extent that the hood 25 115 forces the valve-rod 20 and lever down to a point until the lever 21 contacts and actuates the lever 82, whereby the gate 80 is raised through the rod 81.

Having thus fully described our said invention, what we desire to secure by Letters Patent, is—

1. In an acetylene gas generator, the combination, with the generator casing, of a carbid holding receptacle arranged so as to discharge its contents into said casing, a gate arranged within said carbid holding receptacle for separating and constraining a portion of the carbid apart from the main mass, a rod connected to the gate and extending 125 130

above the receptacle, said rod being actuated by an abnormal depression of the hood for elevating said gate and releasing the constrained carbid after the main mass of car-

5 bid is discharged.

2. In an acetylene gas generator, the combination, with the generator casing, of a carbid holding receptacle having a discharge opening arranged to discharge the carbid 10 into said casing, a valve for controlling the flow of carbid through said discharge opening, a valve-stem for mounting said valve, a hood for inclosing said carbid receptacle and operating the valve-stem by the lower- 15 ing of the hood, a gas holding bell communicating with said casing, means actuated by said gas bell for depressing the hood, a gate arranged within said carbid holding

receptacle for separating and constraining a portion of the carbid apart from the main 20 mass within said receptacle, a rod connected to the gate and extending above the carbid holding receptacle, said rod being actuated by an abnormal depression of the hood for elevating said gate to release the impounded 25 carbid, after the main mass is discharged.

In witness whereof we have hereunto set our hands and seals at Indianapolis, Indiana, this 4th day of April, A. D. one thousand nine hundred and fourteen.
